UNITED STATES PATENT OFFICE.

ISIDORE HIRSCH, OF NEW YORK, N. Y.

MEANS FOR RENOVATING PRINTERS' TYPE.

Application filed July 18, 1925. Serial No. 44,499.

My invention is designed to afford adequate means whereby printers' type may be quickly and conveniently manipulated for cleansing purposes without disturbing the 5 relative arrangement thereof as distributed to the box compartments of a compositor's ordinary case in which the separate letters of a font of type are segregated in a manner well known in the art, this being attained 10 in a manner hereinafter fully set forth, and the invention consisting primarily and essentially in the specific combination, construction, and arrangement of component parts and appurtenances of the rotatable 15 type-holding and washing apparatus described and claimed, whereby these and other advantageous results are attained.

In the accompanying drawings I illustrate a practical embodiment of the essential 20 features of my invention in type cleaning apparatus of the character designated, comprising a plurality of connected trays formed each with a series of intersticed or reticulated pockets or compartments corresponding in number, and relative arrangement to the individual type box-compartments of the compositor's case in conjunction with which the particular device is to be used, together with reticulated means for 25 retaining the types therein, and for rotating the same, as and for the purpose hereinafter set forth, altogether I do not restrict myself to the identical form and construction of component parts shown by way of exemplification 30 herein, since changes may be made in minor details, and equivalent mechanical expedients resorted to, with like results, and without departing from the spirit and intent of my invention in this respect.

40 In the drawings—

Fig. 1 represents a top view of the open face of a tripartite arrangement of wash-trays, spread on the flat, the openings between the walls of the respective pockets or 45 type receptacles of which correspond in size and shape to those of the type boxes or compartments of the compositor's type case for which the tripartite wash-tray is designed;

Fig. 2 is an end elevation of the wash-tray 50 shown in Fig. 1;

Fig. 3 is a side elevation, partly in section on plane of line 3—3 Fig. 1, representing the tripartite wash-tray shown in Fig. 1 and Fig. 2, as superposed on the type setter case 55 for which this combination is designed;

Fig. 4, is a top view of the tripartite wash-tray shown in Fig. 1, with the reticulated covers applied thereto;

Fig. 5 is a side elevation of the parts shown in Fig. 4,

Fig. 6 is an end elevation of the rotative shaft, showing one of its tray-supporting flanges;

Fig. 7 is an end elevation of the parts shown in Figs. 4 and 5, as folded and secured in closed relationship for rotation in a suitable tank containing a cleansing solution;

Fig. 8 is an isometrical view of one of the 70 reticulated covers;

Fig. 9 is an isometrical view of the rotative shaft and its triangular tray-supporting flanges as positioned on one of the tray covers;

Fig. 10 is a view similar to Fig. 7 showing 75 a modification in which provision is made for a quadruplex combination of wash-tray sections;

Fig. 11 is a detail view showing a means for locking the wash-trays together around 80 the supporting rotor element.

In all but the last figure of the drawings I have, for convenience of exemplification, shown my type renovating apparatus as constructed and arranged in accordance with 85 the form and requirements of a compositor's type case sub-divided by equidistantly positioned transverse partitions into sections in the manner well known in the typographical art, in which latter other divisions of the 90 type setter's case, as well, for instance, as the quadruplex type case indicated as provided for in Fig. 10, may be resorted to, it being understood, of course, in this connection, that my type-cleansing apparatus may 95 be adapted to the requirements of type cases of any plurality of sub-divisions as may be found expedient,—each special form and arrangement of compositor's type case requires a corresponding modification in the 100 construction and arrangement of my type cleansing means.

Hence the distinctive feature of my invention consists essentially in the provision of sub-divisional wash-trays corresponding 105 in shape and number to the divisions of a compositor's type case of a prescribed form and construction, in conjunction with closure means for said wash-trays, and rotative means provided with wash-tray sup- 110

porting means, adapting the washer to the requirements of a particular arrangement of type-setter's case.

Each wash-tray T, is formed with a series 5 of pockets or type receptacles t, t, the entrances to which (indicated particularly in Fig. 1 of the drawings) correspond in size and shape to the type-box compartments c of a compositor's case C.

10 In the tripartite sectional combination of wash-tray T, shown in the drawings, the outer foldable sections are hingedly connected to the inner medial section by pintle rod p, p, extending through eye-knuckle flanges 15 k, provided for the purpose on the conjunctive edges of the trays, the latter also being formed on their narrower end edges with eye-knuckle flanges k¹, for the reception, upon occasion, of longitudinal bolt rods b, b, by means of which the said wash-tray sections T may be temporarily locked in extended position and co-relationship, as shown in Figs. 1 and 3, when it is desired 20 to superpose the tripartite trays upon a 25 compositor's type case C, as indicated in Fig. 3. When thus superposed and clamped together, this temporary combination of wash-tray T and type case C, is reversed, resulting in the transfer of the types from 30 the box-compartments c, in the case C, to the corresponding and coincident type pockets in t, in the wash-tray section T, after which the case C, is disconnected and removed from the wash-trays sections.

35 The type receptacles or pockets t, in the wash-tray T, are deeper and of greater internal area and capacity than the corresponding type box-compartments c, in the compositor's case C, so as to afford ample 40 room for freedom of movement of the types in the pockets during the rotative cleansing operation; and the sides and end walls of 45 said pockets are reticulated to admit of the passage of a cleansing liquid.

50 After the disconnection and removal of the compositor's type case C, from the tray sections, as above stated, the long bolt rods b, b, are withdrawn, and the reticulated covers A positioned over the otherwise open 55 faces of the trays T, and secured thereto by shorter bolt rods b¹, b¹, inserted in the end eye-knuckles k¹, of the wash-trays T, and in the intervening end eye-knuckles a, a, of the reticulated covers A, A, as shown more particularly in Figs. 5 and 7 and 10 of the drawings.

Rigidly attached to the outer side of one 60 of the reticulated covers A, are the angular flanges r, r, of the rotor shaft R. In the tripartite combination of wash-trays illustrated in all figures of the drawings except Fig. 10, the rotor element R, r, r, r, is thus mounted on the medial cover, although this is not material, since said motor element 65 might be so mounted on either of the other

covers with like result in that the covers in any case are foldable as related to each other against the angular wash-tray supporting flanges r, r, of the rotor shaft R. When thus folded over the said supporting flanges r, of the rotor R, the trays are locked thereagainst by means of bifurcated lock pins L, as indicated more particularly in Fig. 11 of the drawings, the parallel arms of the lock pins L being inserted in tabular sockets s, s, integral with the side flanges t, t, of the end wash-trays, said sockets S, S, being shown in solid lines in Figs. 2 and 3 in dotted lines in Fig. 1 of the drawings.

Thus assembled upon and secured to the rotor element R, my type cleansing apparatus, as a unit, is designed to be so mounted upon and in such relation to, a tank containing a suitable cleansing liquid that the rotation of said unit, by means of a suitable mechanical expedient, which insures the immersion, successively, of the wash-trays T, and hence the agitation and cleansing of the types in the pockets t, thereof.

At the conclusion of the washing operation the sectional wash-trays are opened up, the rotor R, and cover A, detached and removed, and with the wash-trays again extended on the flat, as in Fig. 1, the compositor's type case C, is superposed upon and clamped thereto, when the reversal of the wash-trays and compositor's case (thus temporarily reunited) into the relative positions shown in Fig. 3, insures the return of the washed types to their respective box-compartments in said compositor's type case.

The disconnection and removal of the inverted wash-trays from the type case then leaves the cleared type, practically as good 105 as new, in its original relative character arrangement with the case.

Thus by the use of my type washing apparatus as herein set forth, not only the faces, but also other portions of the individual types are cleansed and renovated in such manner as to restore them substantially to their original state and condition as before use, so that prints made therefrom will be clean, clear and perfect,—eliminating 110 the effects of "off feet" conditions incidental to the use of dirty type, as will be readily understood by those conversant, practically, with the art of typography, and thus obviating the former necessity for discarding old type fonts, and their replacement by new fonts,—an expensive expedient as compared with my system of type renovation.

It is to be understood that by the terms reticulated as herein used, I mean to include 115 intersticed or foraminulous structures of any kind adapted to admit of the passage of liquid therethrough although in the present instance they are shown as of wire mesh.

An important incidental advantage of my 120

process of renovation is that the type is thereby restored to its original sanitary condition, so that its manipulation may be effected without danger to the compositor.

5 What I claim as my invention and desire to secure by Letters Patent is:

1. Type cleaning apparatus of the character designated comprising a plurality of hingedly connected wash-trays each formed with a series of reticulated angular type pockets, 10 reticulated covers detachably connected with said wash-trays, and a rotatable shaft formed with angular flange supports for said trays, together with means for se-

curing the latter thereto, substantially in 15 the manner and for the purpose set forth.

2. Type cleaning apparatus of the character designated, comprising three hingedly connected wash trays each formed with a series of reticulated angular type pockets, 20 reticulated covers detachably connected with said type trays and a rotatable shaft formed with triangular flange supports for the said wash-trays, together with means for securing the latter thereto, substantially in the 25 manner and for the purpose set forth.

ISIDORE HIRSCH.
